VIBRATOR

Charles F. Coake, Indianapolis, Ind., assignor to
 Senn Corporation, New Augusta, Ind., a corpora-
 tion of Indiana

Application April 18, 1946, Serial No. 663,200

6 Claims. (Cl. 200—90)

1

This invention relates to electromagnetic vibrators and has for its object to simplify the construction and increase the operating efficiency of such devices.

Another object of the invention is to maintain the maximum contact area between the contacts of an electromagnetic vibrator under all operating conditions.

Another object is to provide a vibrator having a novel combination of inner and outer flexible contact arms in which the ratio of compliances of said arms is such as to maintain their contacting surfaces parallel under all conditions of use.

Still another object is to provide an electromagnetic vibrator of the foregoing type having novel and improved details of construction and features of operation.

Various other objects and advantages will be apparent as the nature of the invention is more fully disclosed.

The invention will be described in its application to a miniature vibrator of the type disclosed in my copending application Serial No. 663,199, filed April 18, 1946, and copending application Serial No. 532,962, filed April 27, 1944 in which a vibratory reed carrying a pair of inner contact arms is enclosed in a compact skeleton frame of cylindrical contour containing a driver coil and a pair of outer contact arms cooperating with the contact arms carried by the reed.

The invention resides in a simplified combination of inner and outer contact arms in a vibrator of the above type, in which the compliances (i. e., the reciprocal of stiffness) of said arms are such as to maintain their power contacts parallel throughout the operating range. By thus maintaining the cooperating contacts parallel and preventing them from rocking on each other, I maintain the maximum contact area under all operating conditions and thereby improve the contact efficiency and prolong the life of the contacts.

Although the novel features which are characteristic of this invention are set forth more in detail in the claims appended hereto, the nature and scope of the invention may be better understood by referring to the following description, taken in connection with the accompanying drawing forming a part thereof, in which a specific embodiment has been set forth for purposes of illustration.

In the drawing:

Fig. 1 is a longitudinal sectional view of an

2

electromagnetic vibrator embodying the present invention; and

Fig. 2 is an exploded perspective view of the frame, vibratory reed and contact assembly of the vibrator.

In the following description certain specific terms are used for convenience in referring to the various details of the invention. These terms, however, are to be interpreted as broadly as the state of the art will permit.

In the drawing, I have shown an electromagnetic vibrator comprising a pair of elongated magnetic frame members 10 supporting a driver coil 11 having a pole piece 12, a vibratory reed 13 secured to clamping base plates 14 which are seated in an insulating disc 15, inner contact arms 16 which are secured to opposite sides of the reed 13, and outer contact arms 17 which are secured to and insulated from the frame members 10 and cooperate with the respective inner arms 16 as hereinafter more fully described.

The magnetic frame members 10 are preferably stamped out of sheet metal and are curved transversely throughout their length. Each frame member has a pair of outwardly extending arms 18 which are secured as by welding to the corresponding arms of the other frame member when the two members are brought together as shown in Fig. 1. The ends of the frame members adjacent the arms 18 comprise arcuate collars 19 which partly surround a disc 11a carrying the driver coil 11 and are secured thereto as by welding. The opposite ends of the frame members 10 are welded to the clamping plates 14, as shown in Fig. 1.

The vibratory reed 13 is formed with an upward taper in width and has an armature 22 of magnetic material secured to its upper or free end as by welding. When the vibrator is assembled, as shown in Fig. 1, the armature 22 is encompassed by the arms 18 of the magnetic frame members 10 and is spaced only slightly from said arms and from the pole piece 12, thus forming a magnetic flux path of low reluctance which increases the sensitivity of the instrument. The lower extremity of the reed ends in two extensions or ears 23 connected with the body of the reed by means of weakened portions 24 constituting hinges which facilitate setting the reed in vibration upon energization of the driver coil 11. The ears 23 of the reed are secured to tabs 26 of the plates 14 as by welding. The depending lugs 26 and the ears 23 are seated in radial slots 27 in the insulating disc 15 when the plates 14 are seated on the disc as shown in Fig. 1.

The two inner contact arms 16, which are secured to opposite sides of the vibratory reed 13, are preferably stamped out of flexible sheet metal and each comprises a pair of spaced parallel resilient side arms 31 having their ends connected by top and bottom yokes or cross arms 32 and 33, respectively, and an inner arm or tongue 34 projecting from the center of the top yoke 32 into the space between the side arms 31 and carrying a contact 35 having a flat contact surface. The bottom yokes 33 are bent transversely along a line 36 and the portions of said yokes below the bend 36 are secured to the reed 13 by riveting or welding, so that the entire contact arm 16 above the bend 36 stands out from the reed 13 at an angle and the two contact arms 16 together form a V-shape as shown in Fig. 1. Since the bend line 36 is in the rigid part of the contact arm below the point where the flexible side arms 31 start, the effective length and tuning of the side arms 31 will remain unchanged even though the precise location of the bend 36 may vary slightly in different stamping operations.

The two outer contact arms 17, in the embodiment illustrated herein, are similar to the inner contact arms 16, and they have therefore been given similar reference numerals, but with primes affixed thereto. However, the outer contact arms 17 are inverted with respect to the inner arms 16 and have their yokes 33' secured by bolts 38 and insulating spacers 39 to the respective frame members 10. The free portions of the outer contact arms 17 project downwardly at an angle to bring the contacts 35' adjacent and parallel to the contacts 35 of the respective inner contact arms 16.

The compliance of the various contact arms 16 and 17 is the sum of the compliances of the component parts of said arms. Considering either of the inner contact arms 16, for example, one of such component parts extends from the base of the free side arms 31 to the line of the contact 35, as designated *a* in Fig. 2. The other component part of said arm 16 is the U-shaped distance *b* from the aforesaid line of the contact 35 up the arm 31, across the yoke 32 and down the arm 34 to the contact 35. Likewise with regard to the cooperating outer contact arm 17, one of the component parts extends from the base of the free side arms 31' to the line of the contact 35' as indicated by *c* in Fig. 2. The other component part of said arm 17 is the U-shaped distance *d* from the line of the contact 35' down the arm 31', across the yoke 32' and up the arm 34' to the contact 35'.

I have discovered that in the case of a vibrator, such as illustrated herein, where both of the cooperating contact arms contain a reverse bend, a ratio of compliances of $a=c$, and $b=d$, will result in maintaining the cooperating contacts 35 and 35' parallel to each other when flexed. Furthermore, in a specific and sometimes preferred case where $a=b=c=d$, the cooperating contacts 35 and 35' will not only remain parallel to each other when flexed, but will also remain in planes parallel to their original plane throughout the operating range. In either case the contacts will always engage in flat face-to-face contact and maintain the maximum contact area under all operating conditions, thereby improving the contact efficiency and prolonging the life of the contacts.

Although a specific embodiment has been shown and described herein for purposes of illustration,

it will be evident to those skilled in the art that the invention is capable of various modifications and adaptations within the scope of the appended claims.

5 What is claimed is:

1. An electromagnetic vibrator comprising a vibratory reed, a pair of inner contact arms carrying contacts mounted on opposite sides of said reed, and a pair of rigidly supported outer contact arms carrying contacts for engagement with the contacts of the respective inner contact arms, each of said contact arms having a pair of resilient side arms, a yoke connecting the free ends of said side arms, and a tongue projecting from said yoke into the space between said side arms and carrying the aforementioned contact the cooperating inner and outer contact arm being mounted to extend in opposite direction from their fixed ends and having a ratio of compliances selected to maintain their cooperating contacts parallel.

2. An electromagnetic vibrator comprising a vibratory reed, a pair of inner contact arms carrying contacts mounted on opposite sides of

25 said reed, and a pair of rigidly supported outer contact arms carrying contacts for engagement with the contacts of the respective inner contact arms, each of said contact arms having a pair of

30 resilient side arms, a yoke connecting the free ends of said side arms, and a tongue projecting from said yoke into the space between said side arms and carrying the aforementioned contact the cooperating inner and outer contact arm being mounted to extend in opposite direction

35 from their fixed ends and having a ratio of compliances selected according to the formulae $a=c$ and $b=d$, where *a* and *c* represent the compliances of the side arms of the cooperating contact arms from their supports to their contact

40 lines, and *b* and *d* represent the compliances of the cooperating contact arms from said contact lines around the yokes to the contacts themselves

3. An electromagnetic vibrator comprising a vibratory reed, a pair of inner contact arms carrying contacts mounted on opposite sides of

45 said reed, and a pair of rigidly supported outer contact arms carrying contacts for engagement with the contacts of the respective inner contact arms, each of said contact arms having a pair of

50 resilient side arms, a yoke connecting the free ends of said side arms, and a tongue projecting from said yoke into the space between said side arms and carrying the aforementioned contact the cooperating inner and outer contact arms

55 being mounted to extend in opposite directions from their fixed ends and having a ratio of compliances selected according to the formula

$$a=b=c=d$$

60 where *a* and *c* represent the compliances of the side arms of the cooperating contact arms from their supports to their contact lines, and *b* and *d* represent the compliances of the cooperating contact arms from said contact lines around the yokes to the contacts themselves.

4. An electromagnetic vibrator comprising a base plate, a vibratory reed secured to said plate, an armature on the free end of said reed, a

70 U-shaped frame secured to said plate on both sides of said reed, a driver coil secured to said frame and having a pole piece adjacent said armature, a pair of inner contact arms mounted on opposite sides of said reed each having an end 75 yoke secured to said reed, a pair of side arms con-

nected to said yoke, a second end yoke connecting the outer ends of said side arms and a tongue having a flat contact projecting downwardly between said side arms from the center of said second yoke, and a pair of outer contact arms each having an end yoke secured to and insulated from said frame, a pair of side arms connected to said yoke and extending toward said base plate parallel to the inner contact arms, another end yoke connecting the outer ends of said side arms and a tongue having a flat contact projecting upwardly between said side arms from the center of said other end yoke and having a flat contact for engagement with the contacts of the respective inner contact arms.

5. An electromagnetic vibrator comprising a base plate, a vibratory reed secured to said plate, an armature on the free end of said reed, a U-shaped frame secured to said plate on both sides of said reed, a driver coil secured to said frame and having a pole piece adjacent said armature, a pair of inner contact arms mounted on opposite sides of said reed each having an end yoke secured to said reed, a pair of side arms connected to said yoke, a second end yoke connecting the outer ends of said side arms and a tongue having a flat contact projecting downwardly between said side arms from the center of said second yoke, and a pair of outer contact arms each having an end yoke secured to and insulated from said frame, a pair of side arms connected to said yoke and extending toward said base plate parallel to the inner contact arms, another end yoke connecting the outer ends of said side arms and a tongue projecting upwardly between said side arms from the center of said other end yoke and having a flat contact for engagement with the contacts of the respective inner contact arms, the cooperating inner and outer contact arms being selected according to the formulae $a=c$ and $b=d$, where a and c are the compliances of the side arms of said contact arms from their supporting yokes to their contact lines, and b and d are the compliances of said contact arms from said contact lines around the yokes to the contacts themselves.

6. An electromagnetic vibrator comprising a base plate, a vibratory reed secured to said plate,

an armature on the free end of said reed, a U-shaped frame secured to said plate on both sides of said reed, a driver coil secured to said frame and having a pole piece adjacent said armature, a pair of upwardly extending inner contact arms mounted on opposite sides of said reed each having an end yoke secured to said reed, a pair of side arms connected to said yoke, a second end yoke connecting the outer ends of said side arms and a tongue having a flat contact projecting downwardly between said side arms from the center of said second yoke, and a pair of downwardly extending outer contact arms each having an end yoke secured to and insulated from said frame, a pair of side arms connected to said yoke, another end yoke connecting the outer ends of said side arms and a tongue projecting upwardly between said side arms from the center of said other end yoke and having a flat contact for engagement with the contacts of the respective inner contact arms, the compliances of the cooperating inner and outer contact arms being selected according to the formulae $a=c$ and $b=d$, where a and c are the compliances of the side arms of said contact arms from their supporting yokes to their contact lines, and b and d are the compliances of said contact arms from said contact lines around the yokes to the contacts themselves.
